Term of patent 14 years

(Cl. D62—4)

Fig. 1

Fig. 2

Fig. 3

Fig. 1 is a front elevational view of a louvered ventilator embodying my new and ornamental design;

Fig. 2 is a top plan view of the louvered ventilator depicted in Fig. 1; and

Fig. 3 is a fragmentary side sectional view drawn to a somewhat larger scale than the other figures and taken substantially on a line 3—3 in Fig. 1 and in the direction of the arrows to illustrate a detail of contours of portions of the louvered ventilator.

The characteristic features of my design for the louvered ventilator disclosed resides in the beaded portions on each louver having the configuration shown.

I claim:

The ornamental design for a louvered ventilator, substantially as shown and described.
